ABSTRACT OF THE DISCLOSURE

Low-sudsing detergents comprising at least one wash-active agent and a water-insoluble melamine derivative having the formula:

wherein R₁, R₃ and R₅ each represent hydrogen or an organic radical containing 1 to 24 carbon atoms, and R₂, R₄ and R₆ are each an organic radical containing 1 to 24 carbon atoms.

This invention relates to low-sudsing detergents. It more particularly relates to laundry detergents which contain suds inhibitors capable of effectively and lastingly inhibiting suds formation.

Detergents which produce large volumes of suds are known to be unsuitable for use in the modern drum-type washing machines and automatic dishwashers. Strong sudsing action often results, especially at elevated temperatures, in a foaming-over of the wash-water, with a considerable loss of wash-active substances, as well as inconvenience to the user. It has furthermore developed that large amounts of suds interfere with the mechanical agitation of the goods, i.e., laundry and dishes, being cleaned, so that the detergents are not capable of achieving their full cleaning capacities in the machines.

As a result, substances have been added to the high-sudsing detergents and cleaning agents containing anionic wash-active substances of the sulfate or sulfonate type, which are designed to suppress the sudsing or at least to keep it within tolerable limits. Non-ionic wash-active substances, such as the high-molecular ethers and esters of ethylene oxide and propylene oxide condensation products, which have a relatively low sudsing capacity, have already been proposed as such additives. However, mixtures of such non-ionic tensides, anionic substances and washing alkalis still produce suds to a degree that they cannot be used in drum washing machines at temperatures above 60° C. It has also been proposed to add to the detergents and cleansing agents, alkali soaps of fatty acids, particularly those having a chain length of C₁₈ to C₂₂, as suds inhibiting agents. Although in some cases a very effective foam inhibition can be achieved with such substances, they are not universally applicable. When "soft" tap water having a hardness of 5° dH and less is used, the suds-suppressing action of the long-chain fatty acid soaps is inadequate. Furthermore, the suds reduction is limited to certain detergent combinations. For example, it has not been possible hitherto to reduce appreciably the sudsing action of the alkyl sulfates, and for this reason it has not been possible to use these substances (only to a slight extent if at all) in laundry and dishwater de-

tergents. Nevertheless, the use of alkyl sulfates merits special interest because of their good wash-active and physiological properties, as well as their easy biological degradability.

Foam inhibitors of various chemical constitution have also been proposed for use together with the active detergent substances. As yet, no substance has become known which in low concentration brings about an effective and lasting foam suppression, independently of the chemical constitution of the surface-active substance and the content of hardness forming agents in the water, without impairing the cleaning power of the detergent.

It is therefore an object of this invention to provide a detergent composition which is usable for machine washing of laundry and dishes over a broad temperature range and independent of the degree of hardness of the water.

It is another object of the invention to provide a suds inhibitor for use in detergent compositions.

It is still another object of the invention to provide a suds inhibitor for use in detergent compositions effective in low concentrations and independent of the nature of the surface-active component of the detergent and of the degree of hardness of the water.

It is a still further object of the invention to provide solid and liquid detergent compositions containing water-insoluble melamine derivatives as suds inhibitors.

Other and additional objects of this invention will be apparent from a full consideration of this entire specification including the claims appended hereto.

In accordance with the invention, it has now been found that water-insoluble melamine derivatives of the general formula

wherein R₁, R₃ and R₅ each represents hydrogen or an organic radical containing 1 to 24 carbon atoms, and R₂, R₄ and R₆ each represents an organic radical containing 1 to 24 carbon atoms, can be used as foam inhibitors for detergents and cleaning agents. The organic radicals suitably consist of straight or branched chain aliphatic, cycloaliphatic or aromatic hydrocarbons, and can contain hetero atoms such as nitrogen, oxygen or sulfur atoms, or additional substituents such as halogen atoms. They cannot, however, have any water-solubilizing groups.

The aliphatic radicals can be alkyl or alkylenes groups, for example, methyl, ethyl, propyl, butyl, hexyl, octyl, decyl, dodecyl, tetradecyl, hexadecyl, octadecyl, propylene, butylene, decylene, octadecylene, etc. As cycloaliphatic radicals, the following may be mentioned: cyclohexyl, cyclohexenyl, alkyl-substituted cyclohexenyl, etc. Illustrative of aromatic and araliphatic hydrocarbon radicals within the scope of the invention are phenyl, naphthyl, diphenyl, alkylphenyl, in which the alkyl group contains from 1 to 20 carbon atoms. Exemplary instances of alkylphenyl include tolyl, xylencyl, hexylphenyl, dodecylphenyl, etc.

Thereby in the melamine molecule the substituents can be the same or different, that is, the substituents can be entirely or partially aliphatic, cycloaliphatic, aromatic or araliphatic. If the groups R₁—R₆ contain hetero atoms, these can be in the form of amino, nitro, ether, ester, carbonyl, and thioether groups. The preparation of symmetrical and unsymmetrical substituted melamine derivatives is described in Journal of American Chemical Society, vol. 73 (1951), pp. 2981 to 2986; Journal of Organic Chemistry, vol. 26 (1961), pp. 2786 to 2789.

The aforesaid compounds which will be referred to hereinafter as "melamine derivatives" for the sake of brevity, can be produced in the known manner, as for example by the reaction of cyanuric acid chloride with a primary or secondary amine having the above-designated number of carbon atoms or with a mixture of such amines. As melamine derivatives having only short-chained substituents are not very effective, the two radicals on at least one of the amine nitrogen atoms should contain together at least 6 and preferably 8 to 20 carbon atoms.

Of particular practical importance in accordance with the invention are melamine derivatives in which R_1 , R_3 and R_5 each represents hydrogen, and R_2 , R_4 and R_6 each represents straight-chain saturated or unsaturated hydrocarbons having a chain length of C_4 to C_{24} , and preferably C_8 to C_{20} . Such melamine derivatives are formed in the reaction of cyanuric acid chloride with a three molar quantity of alkylamines of the stated chain length. Alkylamines having 8 to 24 carbon atoms can be obtained, for example, in the prior art manner from naturally occurring fatty acid mixtures, such as coconut, palm nut and tallow fatty acids, rape-oil fatty acids and other fatty acids of vegetable or animal origin.

The foam retardant action of the melamine derivatives is greatly dependent on temperature. Depending on the structure of the radicals R_1 to R_6 , it does not begin to be fully effective until above a certain temperature range corresponding approximately to the fusion point of the melamine derivative. Melamine derivatives in which the radicals R_1 to R_6 are unalike, that is, in which R_1 to R_6 consist of saturated or unsaturated alkyl radicals of different chain length, exhibit a wax-like behavior; they do not have a sharp fusion point and they soften or melt within a temperature range from about 5 to 40° C. The foam reduction produced by the melamine derivatives which are present in the solid state is less than that produced when they are used in the liquid or semisolid state. As the temperature increases, foam inhibition is increased to the extent that the initially solid melamine derivative softens or melts, reaching its full value as soon as the fusion point is exceeded.

The temperature range in which the melamine derivatives become effective increases with the number and chain length of the substituents. For the purposes of the invention, preference is given to melamine derivatives which at 100° C. are in the completely fused state. For this purpose, the total number of carbon atoms contained in the substituents R_1 to R_6 should not amount to more than 72, and preferably not more than 60.

By the selection of appropriate substituents or by mixing different melamine derivatives each of uniform structure, it is possible to a great extent to adapt the melting range to practical requirements, and with it the onset of a heavy breakdown of suds. For example, fine detergents which produce large quantities of suds are often desired because the suds interfere with the mechanical working of the goods, which in the case of delicate wool and silk fabrics may promote matting and similar deterioration. Mixtures that can be used equally as fine detergents and as boiling detergents are advantageously so adjusted that they foam moderately to well in the fine laundry range, i.e., at temperatures between 20 and 50° C., while at a high temperature, especially around 100° C., the suds formation is substantially suppressed. In such formulations, it is desirable to use for the suds regulation, melamine derivatives in which the radicals R_1 , R_3 and R_5 consist of hydrogen, and the radicals R_2 , R_4 and R_6 have an average alkyl chain length of C_{10} to C_{16} . The softening or melting range of these melamine derivatives generally lies between 25 and 60° C.

A foam reduction that is substantially independent of temperature can be achieved on the one hand by the use of melamine derivatives having a very broad fusion range, but on the other hand also by combining two melamine

derivatives one of which is of low molecular weight and melts at low temperature, while the other has long-chained substituents and melts at relatively high temperature. Melamine derivatives of low molecular weight, e.g., melting at 10 to 30° C., exhibit a decrease in their activity as soon as temperatures above 70 to 90° C. are reached, while the high melting product, which is less active at lower temperatures, develops its full effect at the increased temperature.

10 The anti-foaming agents of the invention are suitable for use with many different kinds of anionic, ampholytic, cation-active and non-ionic wash-active substances. The anionic substances are exemplified by alkali soaps of fatty acids, and fatty acid condensation products such as derivatives of aminocarboxylic acids; tensides of the sulfate or sulfonate type such as primary or secondary alkyl sulfates, fatty acid alkanolamide sulfates, fatty acid isothionates, fatty acid taurides, alkanesulfonates and olefin sulfonates, alkylbenzenesulfonates, alpha-sulfo-fatty acid esters, etc. The melamine derivatives are also effective in relation to ampholytes are exemplified by alkylbetaines and alkylsulfobetaines, and in relation to cation-active tensides such as quaternary ammonium salts. Furthermore, they can be combined with non-ionic wash-active substances such as alkyl and acyl polyglycol ethers, alkylphenol polyglycol ethers, fatty acid sugar esters, aminoxides, fatty acid alkanolamides and other fatty acid condensation products, as well as with saponines.

30 The detergents and cleaning agents containing the melamine derivatives can also contain the customary fillers and additives in addition to the above-named surface-active compounds. These include the wash alkalis and, in particular, the orthophosphates, pyrophosphates and more highly condensed phosphates as, for example, tetrasodium and tetrapotassium pyrophosphate, penta-sodiumtriphasphate, pentapotassiumtriphasphate, sodium-tetrametaphosphate, sodium hexametaphosphate, etc., as well as mixtures thereof; silicates, carbonates, borates and hydroxides of alkalis; oxygen-yielding or active chlorine 40 bleaches such as sodium perborate, hydrogen peroxide, carbamic peroxide, dichlorocyanuric acid, etc.; complex formers such as polyaminopolycarboxylic acids, as for instance ethylene diaminotetraacetic acid, nitriloacetic acid, etc.; stabilizers as for instance magnesium silicate and neutral salts. Other additives include dirt-dispersing 45 agents, particularly cellulose derivatives such as cellulose glycolate, methyl cellulose and the like, and optical brighteners as well as perfumes and colorants. These 50 additives have no substantial influence on the foam-suppressing action of the melamine derivatives.

The quantities of melamine derivatives to be used in the detergent or cleansing composition depends on the quantity of the surface-active or wash-active substance 55 present, and on the magnitude of the effect desired. The concentrations that are important in practice range from 0.1 to no more than 20 percent of the weight of the wash-active substance. It is, of course, possible to use still greater amounts of the melamine derivative, as for example amounts of as much as 50% of the weight of wash-active substance for suppressing the sudsing action almost completely, but this is usually unnecessary with detergents.

60 The special advantage of the melamine derivatives is to be seen in the fact that, even in low concentration, they produce a considerable foam suppression with all of the known wash-active substances, both in hard and in soft water, without diminishing the washing action. It is of special importance in practice that in this manner controlled suds detergents for use in machine-washing and dishwashing detergents can be manufactured on the basis of fatty alcohol sulfates. Furthermore, the additives of the invention do not impair the pulverulent qualities 65 of detergents, and can easily be incorporated into the

detergent concentrates prepared by spray-drying or into prepared liquid detergents.

It is particularly advantageous to mix the melamine derivatives with the solid detergents or with a component thereof. This can be done, for example, by mixing the finely divided solid, or liquid, or fused melamine derivatives, or melamine derivatives dissolved in organic solvents, as the case may be, with the powdered or granulated detergent or a part thereof, such as the sodium perborate, or by spraying them onto same.

In accordance with the foregoing, the melamine derivatives contained in the detergent are present in a coarsely dispersed state and are found for the most part on the surface of the detergent components. Because of their wax-like, plastic characteristics, the melamine derivatives are substantially agglomerated and fuse with the detergent components and thus no tendency toward decomposition.

It is also possible to provide that the melamine derivatives at least envelop the detergent components. Particularly those preferred detergents comprise oxygen- or active chlorine-containing bleaches, in which the powdered or granulated bleach particles, preferably sodium perborate, are covered by a coating of the claimed melamine derivatives. The coating of the detergent particles may be accomplished by the methods well known in the art, for example, by maintaining the detergent components in a state of constant movement in the conventional mixing, granulating or coating devices and simultaneously adding thereto and/or spraying thereon the melamine derivative in finely divided or fused form. If sodium perborates are employed, a melamine derivative coating will prevent the specifically heavier perborate body from separating and/or disintegrating from the specifically lighter particles of the detergent powder during packaging, storage or transport.

The melamine derivatives may also be used as a wax-like coating on the detergent tablets, thus, simultaneously, protecting the tablets from untimely decomposition, as for example due to atmospheric variations.

In the following Examples 1 to 8 and 21, the sudsing action of solutions of detergent compositions in accordance with the invention was measured by the DIN method (DIN 53,902). This method makes it possible to establish the foam inhibiting action of the melamine derivatives herein taught. The foam volume was read 30 seconds after the beating machine had been shut off and was again read after 5 and 10 minutes to determine the extent of the collapse of the foam. Instances in which the maximum readable foam volume of 590 ml. were observed are indicated in the tables by the abbreviation "max."

However, since with the above DIN method it is not possible to determine directly the performance of the washing solutions in closed drum washing machines at temperatures between 60 and 100° C., an apparatus was used in Examples 9 to 20 which had been developed on the basis of the applicants experience with dishwashing and clothes-washing machines and which is capable of results closely approaching that in actual use of the conventional machines. The construction of the apparatus which will be referred to hereinafter as the "foam tester," is now described.

It consists of a cylindrical vessel of high-grade steel having an inside diameter of 44 cm. and an inside depth of 85 cm., which is surrounded by a double jacket provided with an insulating material. The vessel is sealed with a lid containing a vent tube. About 5 cm. below the upper rim is an annular tube which is equipped with numerous downwardly directed outlet orifices, and which is connected by a supply line and a pump having a pumping capacity of about 160 to 180 liters per minute, with the bottom of the vessel. The depth of the foam can be observed by means of two oppositely located windows, the front one of which is graduated. The testing appara-

tus is furthermore equipped with an electrical heating element, stop-cocks for filling and emptying the vessel, a thermometer, and a thermostat for keeping the temperature constant.

The sudsing test is carried out as follows:

34 liters of solution are introduced into the vessel and heated to the testing temperature. The suds are produced by 2 minutes of constant recirculation of the solution. Immediately thereafter the depth of the foam is read off. The maximum measurable suds depth is 590 mm., at which point the foam line reaches the tube. Any rise above this limit is also indicated in the following tables by the abbreviation "max."

The following examples are set forth as illustrative of the instant invention and should be in no way construed as limitative of the scope thereof. In the examples, unless otherwise stated, the percentage figures are percentages by weight. The percentage amounts of melamine derivative refer to the total amount of powdered or liquid product used.

Example 1

(a) A solution having the following composition was made to foam at 60° C. by the DIN method:

1.5 g. n-dodecylbenzenesulfonate (sodium salt)
3.5 g. sodium sulfate
1 l. water

(b) To this solution, 0.5 g. of a melamine derivative was added, which had been obtained by the reaction of 1 mol of cyanuric chloride with 3 mols of a mixture of primary alkylamines having a chain length of C₁₂ to C₁₈ (average chain length C_{13.5}), (R₁, R₃ and R₅=hydrogen). The fusion range amounted to from 27 to 62° C.

The results of the test procedure are set out in the following table:

TABLE I

Water Hardness	ml. of foam volume after—		
	30 sec.	5 min.	10 min.
(a) 0° dH.....	max.	max.	310
20° dH.....	max.	590	540
(b) 0° dH.....	70	40	20
20° dH.....	60	30	20

Example 2

Example 1 was repeated, but in place of the n-dodecylbenzenesulfonate, the same quantity of fatty alcohol sulfate (chain length—C₁₂ to C₁₈, average chain length—C₁₄) was used. The results of these tests are set out in the following table:

TABLE II

Water Hardness	ml. of foam volume after—		
	30 sec.	5 min.	10 min.
(a) 0° dH.....	max.	590	500
20° dH.....	max.	590	500
(b) 0° dH.....	100	50	20
20° dH.....	100	60	20

Example 3

(a) 5 g. of the following detergent mixture were dissolved in one liter of water and foamed at 60° C. by the DIN method.

15% n-dodecylbenzenesulfonate (sodium salt)
3% fatty alcohol polyglycol ethers (alkyl chain length—C₁₂ to C₁₈ (10 ethylene glycol groups))
45% penta sodium triphosphate
1% carboxymethylcellulose (sodium salt)
Remainder: sodium sulfate and water.

(b) The same experiment was repeated following the addition of 5% of the melamine derivative as set out in Example 1. [i.e., 5% of the detergent mixture consisted

of the melamine derivative.] The results are set out in the table which follows:

TABLE III

Water Hardness	Ml. of foam volume after—		
	30 sec.	5 min.	10 min.
(a) 0° dH	530	250	70
20° dH	550	290	70
(b) 0° dH	10	0	0
20° dH	10	0	0

Example 4

(a) A low-sudsing machine detergent having the following composition was foamed by the DIN method at 60° C. (concentration 5 g./l.):
 7.5% n-dodecylbenzenesulfonate (sodium salt)
 7.5% soap (sodium salt)
 5.0% fatty alcohol polyglycol ethers (10 ethylene glycol groups)
 1.5% carboxymethylcellulose (sodium salt)
 40% penta sodium triphosphate
 Remainder: silicates, perborate and water.

(b) 5% of the melamine derivative used in Example 1 was added to the above mixture and foaming produced as in (a). The results are set out in the following table:

TABLE IV

Water Hardness	Ml. of foam volume after—		
	30 sec.	5 min.	10 min.
(a) 0° dH	530	520	430
20° dH	80	50	40
(b) 0° dH	10	0	0
20° dH	15	10	0

The data show that the anti-foaming agent based on soap and polyglycoether was effective only in hard water, while the melamine derivative completely suppressed the foam in both hard water and soft water.

Example 5

(a) A solution of 5 g. of saponin per liter of water (20° dH) was treated at 60° C. by the DIN method.
 (b) The same experiment was repeated but with the addition of 0.5 gram per liter of the melamine derivative of Example 1. The results are set out in the following table:

TABLE V

	Ml. of foam volume after—		
	30 sec.	5 min.	10 min.
(a)-----	510	540	540
(b)-----	20	10	10

The data established that the addition of the melamine derivative substantially completely suppressed foam formation.

Example 6

(a) A solution of 5 g./l. of an amphotolytic tenside having the formula

was treated by the DIN method at 60° C.

(b) The experiment was repeated following the addition of 0.5 g./l. of the melamine derivative used in Example 1.

The results are set out in the following table:

TABLE VI

Water Hardness	Ml. of foam volume after—		
	30 sec.	5 min.	10 min.
(a) 0° dH	580	580	330
20° dH	max.	max.	320
(b) 0° dH	140	110	90
20° dH	380	310	120

Example 7

(a) Solutions containing 5 g./l. of cation active tensides were foamed at 60° C. by the DIN method and the foam depth was read after 30 seconds.

(b) The same experiment was repeated following addition of 0.5 g./l. of the antifoaming agent described in Example 1 to the solutions.

The results are set out in Table VII which follows:

TABLE VII

	Ml. of foam volume after 30 seconds	
	0° dH	20° dH
Alkyldimethylbenzylammonium chloride (Alkyl=C ₈ to C ₁₈):		
(a)-----	550	350
(b)-----	20	20
N-laurylpypyridinium chloride:		
(a)-----	420	500
(b)-----	30	0

Example 8

A boiling detergent having the following composition:
 12–14% n-dodecylbenzenesulfonate (sodium salt)
 3–4% oleyl alcohol polyglycol ether (10 ethylene glycol groups)

40–45% pentasodium triphosphate

5–6% sodium silicate (Na₂O·3.3 SiO₂)

3% magnesium silicate

0.5–1.5% carboxymethyl cellulose (sodium salt)

14–16% sodium perborate

Remainder: Neutral salts, optical brighteners, perfumes, water,

was found to form excessive suds at temperatures above 40° C., in experiments carried out in the above-described suds testing apparatus. It therefore was unsuitable for drum-type washing machines. When 0.5 to 7.5 wt. percent of the melamine derivative described in Example 1 was added to the above mixture, a controlled-suds machine detergent was obtained which did not form excessive suds in hard or in soft water.

When used in a concentration of 5 g./l., in hard and soft water (0° and 15° dH), it had the following foam characteristics at the various temperatures shown:

TABLE VIII

Percentage added	Depth of suds in mm.					
	19° C.	38° C.	58° C.	76° C.	93° C.	97° C.
None-----	275	475	max.	max.	max.	max.
0.5%-----	280	380	560	480	280	270
1.0%-----	235	365	420	315	175	140
2.5%-----	220	380	160	60	30	10

7.5%-----	220	245	40	35	15	5

Example 9

Example 8 was repeated, but in place of the alkylbenzenesulfonate used in that example the same amount of a sodium fatty alcohol sulfate (alkyl chain length C₁₂ to C₁₈) was used. In water of 15° dH, the following sudsing characteristic was found:

TABLE IX

Percentage added	Depth of suds in mm.					
	19° C.	38° C.	58° C.	76° C.	93° C.	97.5° C.
No e-----	310	470	max.	max.	max.	max.
1.0%-----	255	360	180	125	85	80
2.5%-----	225	230	130	85	55	40
5.0%-----	230	260	60	20	15	5

Example 10

A detergent as described in Example 8 but in which the alkylbenzenesulfonate had been replaced by salts of α-sulfo fatty acid esters—that is, the detergent contained 8% of a sodium salt of an α-sulfo-fatty acid methyl ester prepared from hydrogenated palm kernel fatty acid, and

5.5% of a sodium salt of an α -sulfo-stearic acid methyl ester—was tested.

The following sudsing characteristics were determined using the suds testing apparatus above described and using the melamine derivative described in Example 1 (15° dH):

5

TABLE X

Percentage added	Depth of suds in mm.					
	19° C.	38° C.	58° C.	76° C.	93° C.	97.5° C.

30

Example 16

One-half of the dodecylbenzenesulfonate in the detergent composition of Example 8 was replaced with the sodium salt of a tallow fatty alcohol sulfate having a chain length of C_{16} to C_{18} . In addition to the melamine derivative used in Example 1 (average carbon number in the side chains= $C_{13.5}$), a melamine derivative with an average carbon number of C_{17} , which had been prepared in a similar manner by the reaction of cyanuric chloride with alkylamines from tallow fatty acids and had a melting range of 30 to 70° C., was also used as an anti-foaming agent. The following sudsing characteristics were observed in the suds testing apparatus in water of 15° dH:

40

45

Example 17

A melamine derivative was employed, which had been made by the reaction of 1 mol of cyanuric acid chloride with 3 mols of a mixture of alkylamines having a chain length of C_8 to C_{12} (average chain length C_{10}). The sudsing characteristics were determined using the above described suds tester and water of 0° and 15° dH.

50

I. designates a detergent according to Example 8.

II. designates a detergent according to Example 9.

These detergents were used in a concentration of 5 g./l.

5%-----	150	370	520	540	380	270

Example 21

A melamine derivative was used, in which R₁, R₃ and R₅ each was represented by hydrogen, and R₂ and R₄ were each represented by alkyl chains having 12 to 18 carbon atoms, and R₆ was a radical of the formula:

The sudsing characteristics were determined by the DIN method at 60° C. in water of 0° dH. Detergent I was a detergent according to Example 8, and detergent II a detergent according to Example 9. A concentration of 5 grams per liter was used in each instance.

TABLE XXI

Percentage added	Ml. of foam after-		
	30 sec.	5 min.	10 min.
I. None-----	max.	560	400
5%-----	130	80	40
10%-----	70	50	30
II. None-----	560	560	520

10%-----	60	40	35

Example 22

The following experiments were carried out in a fully automatic household washing machine having a horizontally mounted drum and viewing window (Model: "MIELE Automatic 410"). A scale was mounted on the viewing window with divisions in millimeters to indicate the depth of suds; the depth to the overflow amounted to 170 mm. The machine was filled with 4 kg. of dirty

70

12

laundry (table linens and underclothing) and 20 liters of washing solution. The detergent contained:

	Percent
Sodium-n-dodecylbenzenesulfonate	7.5
Sodium fatty alcohol sulfate (C ₁₂ -C ₁₈)	7.5
Oleyl alcohol polyglycol ether (10 ethylene glycol groups)	3.5
Sodium silicate (Na ₂ O · 3SiO ₂)	5
Magnesium silicate	3
Carboxymethylcellulose (sodium salt)	1
Foam inhibitor	2.6
Water	7.5
Neutral salts, optical brighteners, perfumes	2.4

The detergent had been prepared by spray drying a concentrate containing about 45% water. Thereafter, 15% sodium perborate tetrahydrate was added with mixing. The following were used as foam inhibitors:

- (a) 2.6% of a melamine derivative according to Example 16 (R₁, R₃, R₅=hydrogen, R₂, R₄ and R₆=alkyl C₈-C₁₂; melting range 25 to 36° C.)
- (b) 2.6% of a melamine derivative according to Example 17 (R₁, R₅, R₃=hydrogen, R₂, R₄ and R₆=alkyl C₁₆-C₁₈; melting range 30 to 70° C.)
- (c) 2.6% of a mixture of equal parts of a and b.

The items to be laundered were first given a preliminary washing at a temperature of 20 to 30° C. using a detergent concentration of 5 g./l., then the water was pumped out and the goods were washed with a new 30 formulation at a temperature of 98° C. and a detergent concentration of 7.5 g./l.

While the detergent without inhibitor over-sudsed in all temperature ranges, the detergent containing inhibitor showed the following suds depths:

35

	Suds Depth in mm.						
	25° C.	30° C.	40° C.	50° C.	60° C.	80° C.	98° C.
40 (a)-----	45	65	80	80	80	125	160
(b)-----	150	160	165	80	70	80	70
(c)-----	70	80	90	85	50	60	75

In test a, the detergent produced less suds in the fine laundering range and more in the boiling laundry range, while its behavior is the opposite in test b. The detergent used in b would consequently be a universal detergent capable of producing much suds at low temperatures and little, if any, suds at high temperatures. Test c indicates a sudsing action that is largely independent of the temperature.

Example 23

A detergent according to Example 22 and a foam inhibitor according to Example 22c were used in this experiment. In this case, however, the foam inhibitor was not mixed into the liquid detergent mixture and then spray-dried to form a concentrate, but was sprayed in the fused state onto the dry sodium perborate and together with the latter was mixed into the washing powder.

The sudsing action was tested as described in Example 22 in a drum washing machine containing dirty laundry. The results are summarized in the following table. The results of Example 22c have been included for comparison:

65

TABLE XXIII

Foam Inhibitor	Suds Depth in mm.						
	25° C.	30° C.	40° C.	50° C.	60° C.	80° C.	98° C.
23(a)-2.6%	0	0	0	0	0	0	10
23(b)-1%	60	70	90	80	60	70	80
22(c)-2.6%	70	80	90	85	50	60	75

The melamine derivative added after spray-drying demonstrates a considerably augmented effect.

The composition of the detergents in which the foam inhibitors of the invention preferentially find use can vary within wide limits. For example, solid or powdered, low-sudsing detergents suitably contain the following as principal components:

5-60% anion-active, amphotolytic or non-ionic wash-active substances and mixtures thereof;

0.1-10% melamine derivative

0-90% inorganic wash-active salts, such as for example anhydrous phosphates, alkali silicates and alkali carbonates;

0-25% per compounds;

0.1-5% dispersing agents of high molecular weight such as carboxymethylcellulose;

0-1% colorants and perfumes as well as optical brighteners;

also stabilizing agents for percompounds, inorganic neutral salts and moisture.

Liquid detergents suitably contain:

5-50% anionic, amphotolytic or non-ionic wash-active substances and mixtures thereof;

0.1-10% melamine derivative;

0-35% anhydrous phosphates, preferably as potassium salts;

0-10% solubilizers, preferably alkylbenzenesulfonates having lower alkyl groups;

0-1% colorants and perfumes, and optical brighteners; also water, and if desired, organic solvents.

The action of the melamine derivatives, however, is not limited to the detergent compositions and quantity ratios stated above and in the examples.

We claim:

1. A low sudsing detergent consisting essentially of at least one wash-active agent selected from the group consisting of anionic, amphotolytic, cation-active and non-ionic wash-active substances and 0.1 to 20% referred to the weight of the wash active agent of a water-insoluble melamine derivative of the formula:

wherein R₁, R₃ and R₅ each represents a member selected from the group consisting of hydrogen and organic radicals containing 1 to 24 carbon atoms, and R₂, R₄ and R₆ each represents an organic radical containing 1 to 24 carbon atoms wherein at least one of the groups of R₁ plus R₂, R₃ plus R₄ and R₅ plus R₆ contains a total of at least 6 carbon atoms and wherein the total number of carbon atoms contained in said groups R₁-R₆ does not exceed 72, said organic radicals R₁-R₆ being free of any water-solubilizing groups.

2. A low sudsing detergent according to claim 1 wherein at least one of the group of R₁ plus R₂, R₃ plus R₄, and R₅ plus R₆ contains from 8 to 20 carbon atoms.

3. A low sudsing detergent according to claim 1 wherein R₁, R₃ and R₅ each represents hydrogen and R₂, R₄ and R₆ each represents a hydrocarbon group containing 4 to 24 carbon atoms.

4. A low sudsing detergent according to claim 1 wherein R₁, R₃ and R₅ each represents hydrogen and R₂, R₄ and R₆ each represents a hydrocarbon group containing 8 to 20 carbon atoms.

5. A low sudsing detergent according to claim 1 wherein R₁, R₃ and R₅ each represents hydrogen and R₂, R₄ and R₆ each represents a hydrocarbon group containing 10 to 16 carbon atoms.

6. A low sudsing detergent according to claim 1 wherein the total number of carbon atoms contained in said substituents R₁-R₆ does not exceed 60.

7. A low sudsing detergent according to claim 1 wherein said water-insoluble melamine derivative is present in an amount of from 0.1 to 10% referred to the weight of the wash-active agent.

8. A low sudsing detergent according to claim 1 wherein said water-insoluble melamine derivative is present in a coarsely dispersed state at least in part affixed on the surface of said wash-active agent.

9. A low sudsing detergent according to claim 1 containing sodium perborate wherein said sodium perborate is covered with a coating comprising said water-insoluble melamine derivative.

10. A low sudsing detergent according to claim 1 wherein said wash-active agent is present in tablet form, said tablet being covered with a coating comprising said water-insoluble melamine derivative.

11. A low sudsing detergent according to claim 1 consisting essentially of

5-60% wash-active agent selected from the group consisting of anionic, amphotolytic, cation-active and non-ionic wash-active substances,

0.1-10% water-insoluble melamine derivative of the formula:

wherein R₁, R₃ and R₅ each represents a member selected from the group consisting of hydrogen and organic radicals containing 1 to 24 carbon atoms, and R₂, R₄ and R₆ each represents an organic radical containing 1 to 24 carbon atoms,

0-90% inorganic alkaline salt

0-25% per compound

0.1-5% dispersing agent

0-1% of at least one member selected from the group consisting of colorants, perfumes, and optical brighteners in solid form.

12. A low sudsing detergent according to claim 1 wherein said wash-active agent is present in pulverulent form at least a part thereof being coated with said water-insoluble melamine derivative.

13. A low sudsing detergent according to claim 1 consisting essentially of water and

5-50% wash-active agent selected from the group consisting of anionic, amphotolytic, cation-active and non-ionic wash-active substances,

0.1-10% water-insoluble melamine derivative of the formula

wherein R₁, R₃ and R₅ each represents a member selected from the group consisting of hydrogen and organic radicals containing 1 to 24 carbon atoms, and R₂, R₄ and R₆ each represents an organic radical containing 1 to 24 carbon atoms,

0-35% anhydrous phosphates

0-10% solubilizer

0-1% of at least one member selected from the group consisting of colourants, perfumes, and optical brighteners.

14. A low sudsing detergent according to claim 1 consisting essentially of

12-14% n-dodecylbenzene sulfonate (sodium salt)
 3-4% oleyl alcohol polyglycoether (10 ethylene
 groups)
 40-45% pentasodium triphosphate
 5-6% sodium silicate (Na₂).3.3 SiO₂)
 3% magnesium silicate
 0.5-1.5% carboxymethyl cellulose (sodium salt)
 14-16% sodium perborate
 0.5-7.5 wt. percent of said water-insoluble melamine
 derivative wherein R₁, R₃ and R₅ are each hydrogen
 and R₂, R₄ and R₆ each has a chain length of from
 12 to 18 carbon atoms.

UNITED STATES PATENT OFFICE
CERTIFICATE OF CORRECTION

Patent No. 3,422,020

January 14, 1969

Edmund Schmadel et al.

It is certified that error appears in the above identified patent and that said Letters Patent are hereby corrected as shown below:

In the heading to the printed specification, line 8, after "Germany," insert -- Feb. 11, 1965, H 55,120; --. Column 10, TABLE XVI, first column, line 2 thereof, "C₁₇" should read -- 1% C₁₇ --. Column 14, line 43, cancel "in solid form." and insert the same between lines 43 and 44, at the left-hand margin, same column 14.

Signed and sealed this 17th day of March 1970.
